Term of patent 14 years

(Cl. D58—5)

FIG. 1

FIG. 2

FIG. 3

FIG. 4

FIG. 1 is a front elevational view of a jug showing our new design.

FIG. 2 is a top plan view thereof.

FIG. 3 is a side elevational view thereof.

FIG. 4 is a sectional view taken through line 4-4 of FIG. 1.

The back is a mirror image of the front and the side not shown is the same as the side shown except that the bottom is not bevelled as in FIG. 3.

The characteristic features of this design reside in the configuration shown in full lines on the drawings.

We claim:

The ornamental design for a jug, substantially as shown and described.
